UNITED STATES PATENT OFFICE.

EDWARD J. VON PEIN, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed April 24, 1922. Serial No. 556,304.

This invention relates to improvements in accounting machines and has more particular relation to the type of machine shown and described in Letters Patent of the 5 United States issued to Thomas Carney, May 23, 1893, and October 1, 1901, and numbered 497,860 and 683,877 respectively.

It is an object of this invention to provide mechanism for preventing misadding 10 on the totalizer when an item key is operated by a quick and hard depression.

With this and incidental objects in view, the invention consists in certain novel features of construction and combinations of 15 parts, the essential elements of which are set forth in appended claims, and preferred forms of embodiment of which are herein-after described with reference to the drawings which accompany and form part of the 20 specification.

Of said drawings:

Fig. 1 is a transverse sectional view of the machine showing the improvement.

Fig. 2 is a detail view of the improvement 25 shown in modified form.

Fig. 3 is a detail elevational view of the driving connection between the key coupler and the revolution shaft.

In its general operation and construction, 30 the machine shown in the present application is substantially like that shown in the Carney patents previously referred to.

This machine comprises a series of manipulative devices, such as keys, which operate 35 mechanism for indicating items, entering the items in one or more totalizers, setting up type, and operating a printing mechanism to make a printed record of items.

Item keys 15 (Fig. 1) are pivoted upon 40 a transverse rod 16, and when the forward ends of one or more of them are depressed they engage and rock a key coupler 17 having two lateral projections 18 placed on opposite ends and journaled in side frames 19.

Pivotedly attached to the rear end of each item key 15 is an upright member 20, each formed with a notch 21, adapted, when a key 15 is operated, to engage a transverse rod 22 on a frame 23, pivoted on a transverse rod 24, to rock said frame different distances according to the value of the operated key. 45 The notches 21 are located at varying dis-

tances from the pivotal connection between the uprights and keys, to effect a differential rocking of the frames 23. Attached to 55 the frame 23 is a registering segment 25.

At each operation of the keys 15 (Fig. 3) which imparts an oscillatory motion to the key coupler 17, an upright member 30 is raised and lowered to give a complete revolution to a shaft 31. The key coupler 17 is connected to the upright member 30 by a roller 32 cooperating with a slot 33 formed in the upright member 30, which is provided with a bifurcated end guided on a stud 34 60 and with two opposing racks adapted alternately to mesh with a pinion 35 fastened on the shaft 31. A spring 36 holds the right hand rack in engagement with pinion 35 which relation of rack and pinion is maintained during the upward movement of the member 30 by means of a flange 37 on said member and a cooperating member 38 projecting from the frame of the machine. At the end of its upward movement the member 70 30 is forced to the right by a spring actuated arm 39 and the left hand rack moved into engagement with the pinion, the flanges 37 and 38 cooperating to maintain this relation during the downward movement of said 75 member 30. A ratchet wheel 40 on the shaft 31 and a pawl 41 pivoted on the frame prevent retrograde motion of the shaft 31 after a key 15 has been depressed a predetermined amount.

A cam 42 carried by the shaft 31 (Fig. 1) cooperates with rolls 43 on a bifurcated arm 44 secured to a totalizer frame 45 to rock the pinions 46 of the rotatable elements of the totalizer into engagement with the registering segments 25. The pinion 46 together with a ratchet 47 and a trip cam 48 are fastened to a numeral wheel 49 which is freely mounted upon a shaft 50 journaled in the totalizer frame. A spring actuated retaining pawl 51 cooperates with the ratchet to prevent a retrograde movement of the rotatable elements. As these rotatable elements rotate in a clockwise direction, the trip cam 48 in moving from the nine to the zero position will engage the tripping nose on a pivoted spring pressed trip pawl 52 and force said pawl back against the tension of the spring to cause the shoulder 53 formed

on the upper end of said pawl to disengage from a lug 54 extending laterally from a pivoted spring pressed carrying pawl 55, allowing the forward end of said pawl to 5 lower to a position to engage a tooth of the ratchet 47 and rotate the totalizer rotatable elements of higher order one division of movement. The carrying pawl 55 is mounted on a pivoted lever 56 which carries a 10 roller 57 cooperating with a cam 58 fastened to the revolution shaft 31. All of this is 15 well known in the art and is shown here for illustrative purposes only.

The registering segment 25 in addition to 20 engaging with the totalizer pinion, meshes with a pinion 59. This pinion is fastened to the left hand end of a shaft 60 which extends to the right beyond the frame of the machine proper and on the right hand end 25 carries a printing wheel (not shown) for printing the detail transactions on a strip. All of this is fully described in the patents previously referred to.

The upright member 20 (Fig. 1) is connected to the key 15 by a stud 65 which operates with an opening 66 formed in the upright member. This opening is elongated to permit the upright member to move at a velocity varying from that of the stud 30 65 during the operation of the key 15, and to allow the segment 25 to remain at rest while the totalizer is disengaging from the segment, previous to the retrograde movement of said segment.

35 Freely mounted upon a stud 67 projecting laterally from the upright member is a roller 68 engaging an inclined edge 69 of a plate 70 secured to the key 15 by two spacing studs 71. The spacing studs 71 are substantially as long as the thickness of the member 20, thus spacing the plate 70 from the key a distance equal to the thickness of the member 20. In this manner the plate 40 70 provides a guide for the member 20 and prevents lateral displacement thereof. By depressing the forward end of the key 15, the rear end will be elevated to engage the shoulder 21 of the upright member with the rod 22 and operate the pivoted frame 23. 45 As the shoulder engages the rod, the roller 68 will be forced up the forward incline 69 and thereby increase the velocity of the upright member over that of the key until the roller passes over the peak of the incline 50 55 when, as the roller travels down the rear incline edge 72, the velocity of the upright member will be less than that of the key.

60 The slowing up of the velocity of the upright member near the end of the depression of the forward end of the key, causes a slower rotation of the totalizer rotating elements so that if these elements complete their movement in the nine position during an operation, the velocity of rotation together with the lost motion between the key provided with a portion cooperating with

and the rotating elements in a machine of this type will not cause the trip cam to contact the tripping nose with sufficient force to release the carrying pawl 55 from the shoulder on the trip pawl and overadd on 70 the totalizer.

This form of plate as shown in Fig. 1 is used principally with the keys of higher order which require practically all of the movement of the keys and upright member 75 in actuating the registering segment. This plate functions to speed up the travel of the upright member of a higher order key so that it may be moved slower later in its upward travel. With keys of lower order it is 80 not necessary to speed up the movement of the upright member so a plate 73 (Fig. 2) of different form is used on these keys. This plate is so shaped that the roller 68 moves off the top of the plate downward upon its 85 rear edge 74 at the time the shoulder 21 on the upright member engages the rod 22 of the pivoted frame. The rear edge 74 of the plate and the slot 66 are made longer to permit a relatively longer retarding movement of the upright member.

90 It is not necessary to have separate plates attached to the keys to perform this function, for the keys themselves may be formed to obtain the same results, as is shown in 95 Fig. 3. The separate plates as shown in Figs. 1 and 2 illustrate the improvement added to a key of the form generally used in a machine of this type.

100 While the forms of mechanism herein as shown and described are admirably adapted to fulfill the objects primarily stated, it is to be understood that it is not intended to confine the invention to the forms of embodiment herein disclosed, for it is susceptible of embodiment in various forms all coming within the scope of the claims which follow.

105 What is claimed is:

110 1. In a machine of the class described, the combination of a depressible key, a totalizer having a rotatable element, a totalizer actuator, means operated by said key to engage and drive said actuator, and a connection between said key and said last-named means for moving said means at a velocity relatively slower than said key during the latter part of the depression of said key.

115 2. In a machine of the class described, a manipulative pivoted member for entering items on a totalizer, provided with a portion thereon with angular edges inclined in opposite directions to cause the elements operated by said pivoted member to move first faster and then slower than said pivoted member.

120 3. In a machine of the class described, the combination of a totalizer, an actuator, a differential means for operating the actuator, and manipulative item entering means 125 provided with a portion cooperating with

the differential means to cause said differential means to move at a different speed from that of the item entering means.

4. In combination, an item registering key, an upright member for operating a totalizer actuating means, a projection on one of said elements, and a camming surface on the other of said elements cooperating with said projection for moving said upright member at a variable velocity relatively to said item registering key.

5. In a machine of the class described, the combination of a manipulative pivoted member, a rotatable member, pivoted means for operating said rotatable member, an upright member operating said pivoted means, and means rigid with said manipulative pivoted member for moving said upright member at a variable velocity.

6. In a machine of the class described, the combination of a key member, a member adapted to be actuated thereby, oppositely inclined cam edges on one of said members and means on the other member cooperating with said cam edges to transmit movement from the key member to the actuated member.

7. In a machine of the class described, the combination of a key member, a member adapted to be actuated thereby, a plate secured to one member and constituting in connection with said member a guide for the other member, and a cam edge on said plate for transmitting movement from the key member to the actuated member.

In testimony whereof I affix my signature.

EDWARD J. VON PEIN.
